UNITED STATES PATENT OFFICE.

JOHN O. NEIKIRK, OF LOMBARD, ILLINOIS, ASSIGNOR TO RODGER BALLAST CAR COMPANY, OF CHICAGO, ILLINOIS, A CORPORATION OF MAINE.

RAILWAY CAR.

1,424,770.

Specification of Letters Patent. Patented Aug. 8, 1922.

Application filed May 3, 1920. Serial No. 378,384.

To all whom it may concern:

Be it known that I, JOHN O. NEIKIRK, a citizen of the United States, residing at Lombard, in the county of Du Page and 5 State of Illinois, have invented certain new and useful Improvements in Railway Cars, of which the following is a specification.

This invention relates to railway cars, and primarily to hopper cars of the type especially adapted for the distribution of ballast, although these cars may also be used for other purposes, such as the carrying of commodities.

One object of my invention is to simplify 15 and improve the car construction by reducing the number of sills employed, at the same time making adequate provision for the distribution of the load and of the pulling and buffing strains to the underframe of 20 the car.

Another object is to provide a car of this type in which the hopper is supported in a simple, novel and durable manner.

These and other objects are accomplished 25 by means of the arrangement disclosed on the accompanying sheets of drawings, in which—

Figure 1 is a fragmentary side elevation of a railway car embodying my invention;

30 Figure 2 is a transverse sectional view of the same car; and,

Figure 3 is a vertical longitudinal sectional view of the same car.

The various novel features of my invention will be apparent from the following 35 description and drawings and will be particularly pointed out in the appended claims.

Referring to the figures of the drawings, it will be noted that I have disclosed my invention in connection with a hopper type 40 of car, in which the hopper 10 has sides 11 which converge downwardly and inwardly toward the longitudinal center of the car. The lower portion of one of the hopper sides 45 intermediate the truck wheels 12 is in the form of a door 13 pivoted at 14 and controlled by any suitable door operating mechanism 15. The upper portions 11^a of the hopper side walls 11 are arranged vertically. The hopper end walls include an 50 upper vertical portion 16 and a downwardly and inwardly inclined sloping portion 17.

This hopper, as above described, rests upon an underframe structure, which is 55 composed of two longitudinally extending

sills 18 and cross members 19, the cross members at the trucks between the sills constituting the bolsters, as will be readily understood, so that the bolsters and the longitudinal sills 18 form a framework upon which the hopper rests, the lower portion of the hopper extending downwardly between the longitudinal sills. These longitudinal sills are of size and strength sufficient to carry the entire vertical load of the car, and do, as a matter of fact, carry the greater part of such load; that is, they carry all the vertical load except that which is transmitted downwardly direct to the bolsters. These longitudinal sills also take the entire pulling and buffing strains. It will be noted 60 that these sills are the only longitudinal sills and that the same are located intermediate the positions normally occupied by the usual side sills and usual center sills. 65 These sills 18 are spaced apart a sufficient amount to receive a large portion of the hopper and permit the hopper to occupy a relatively low position, and in this way be of large capacity and at the same time be 70 within the standard height limits for the hopper type of car. As shown, these longitudinally extending sills 18 are vertically arranged, the webs being in parallel planes 75 entirely outside of the wheels 12. These sills 18 include oppositely arranged and oppositely extending angle members secured to the upper and lower edges of the webs of the sill structure.

Secured to the outer sides of the sills 18 are a plurality of bracket or frame members 20 which diverge outwardly and upwardly from the sills and have vertically arranged portions 21 which conform to and are secured to the webs of the longitudinally extending sills 18 and also have upwardly and outwardly inclined portions 22 which conform to and are secured to the downwardly and inwardly converging hopper sides 11. These brackets or frame members 20 extend 90 upwardly and outwardly to the vertically arranged portions 11^a of the hopper and form, with the longitudinally extending sills 18, a basketlike structure for receiving the hopper 10, thereby providing a strong, durable, compact and rigid construction in which the hopper is firmly supported and in which but two longitudinally extending sills take the greater part of the vertical load 95 of the hopper and its contents, and also take 100 105 110

the entire pulling and buffing strains. This arrangement permits of the use of a hopper which is of full capacity and in which the center of gravity is maintained at a low point in a manner to meet all of the requirements. By referring particularly to Figure 1 of the drawings, it will be noted that the longitudinally extending sills increase in depth toward the transverse center 10 of the car to increase the strength thereof at the middle section of the car where the bending strains are greatest.

It is my intention to cover all modifications of the invention falling within the 15 spirit and scope of the following claims.

I claim:

1. In a railway car, a sill structure in which there are only two longitudinally ex-

tending sills, said sills being located outside of the truck wheels and between the normal positions of the regular center sills and side sills, said two longitudinally extending sills taking the vertical load and the pulling and buffing strains.

2. In a railway car, a sill structure, the sole longitudinally extending members of which comprise a pair of spaced sills located outside of the truck wheels, and a hopper supported upon said sills, and having sides sloping inwardly continuously from points outside and above the sills and meeting intermediate the sills.

Signed at Chicago, Illinois, this 17th day of April, 1920.

JOHN O. NEIKIRK.
